US0D1105700S

(12) United States Design Patent (10) Patent No.: US D1,105,700 S
(45) Date of Patent: * Dec. 9, 2025

(54) COMBINATION KEYBOX

(71) Applicant: Jinhua Xinlei Lock Industry Co., Ltd., Zhejiang (CN)

(72) Inventor: Wanqiang Shang, Hebei (CN)

(73) Assignee: Jinhua Xinlei Lock Industry Co., Ltd., Zhejiang (CN)

() Term: 15 Years

(21) Appl. No.: 29/965,101

(22) Filed: Sep. 26, 2024

(51) LOC (15) Cl. 99-00
(52) U.S. Cl.

USPC D99/28

CLAIM

The ornamental design for a combination keybox as shown and described.

DESCRIPTION

FIG. 1 is a front, top, and left perspective view of a combination keybox showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a perspective view thereof, shown in an open position.

The broken lines shown in the drawings represent portions of the combination keybox that form no part of the claimed design.
